(57) **CLAIM**

The ornamental design of the handle arrangement, as shown and described.

DESCRIPTION

FIG. 1 is a right side view of a handle arrangement according to an exemplary embodiment of the present disclosure showing my new design;

FIG. 2 is a left side view of the handle arrangement of FIG. 1; FIG. 3 is a right perspective view of the handle arrangement of FIG. 1;

FIG. 4 is a left perspective view of the handle arrangement of FIG. 1;

FIG. 5 is a rear view of the handle arrangement of FIG. 1; FIG. 6 is a front view of the handle arrangement of FIG. 1; and,

FIG. 7 is a back perspective view of the handle arrangement of FIG. 1.

The broken lines are provided for illustrative purposes only, and form no part of the claimed design. In addition, the portions of the handle arrangement that are not shown in the drawing do not form any part of the claimed design.
